UNITED STATES PATENT OFFICE.

HENRY CLAY LYON, OF HOWARD LAKE, MINNESOTA.

HAMMER.

No. 834,149.

Specification of Letters Patent.

Patented Oct. 23, 1906.

Application filed June 4, 1904. Serial No. 211,108.

To all whom it may concern:

Be it known that I, HENRY CLAY LYON, a citizen of the United States, and a resident of Howard Lake, in the county of Wright and 5 State of Minnesota, have invented a new and Improved Hammer, of which the following is a full, clear, and exact description.

My invention relates to hammers, and more particularly to those of the magazine 10 type, which carry and supply nails in position for driving.

Its principal objects are to provide a simple and effective device of this class.

It consists in the various features and combinations hereinafter described and claimed.

Reference is to be had to the accompanying drawings, forming a part of this specification, in which similar characters of reference indicate corresponding parts in all the figures.

Figure 1 is a side elevation of one embodiment of my invention. Fig. 2 is an end elevation thereof looking from the left in Fig. 1 and partly broken away and in section. Fig. 25 3 is a longitudinal section on the line 3 3 of Fig. 2, showing the elements in the position for driving a nail. Fig. 4 is a similar view, but with the parts in their delivery position; and Fig. 5 is a detail in perspective of the controlling and contact member.

I have here illustrated a hammer comprising, more essentially, a head 10, having a contact-shank 11, claws 12, and a socket 13, by which is carried a handle 14.

35 Mounted on the outer side of the head, which preferably has such a shape as to substantially conform to it, is a casing C, which may be secured in place by screws c. In the outer portion of this casing is situated a magazine-chamber 15, having a supply-opening provided with a cover 16 and held normally closed by a spring 17, contacting with an arm 17^a, projecting from the inner wall of the casing. The magazine-chamber terminates in a 40 throat 18, narrowed longitudinally of the hammer and having at its inner end a feed-opening 19. In the lower portion of the casing beyond this feed-opening is formed a channel 20, having lateral curved walls 21, converging 45 outwardly to a contracted delivery-opening 22. To the wall of the chamber adjacent to the hammer is fixed a plate 21^a, having outwardly-diverging edges, and secured to each of the side walls of the chamber is an inclined cheek-piece 22^a, serving to move the nails toward the plate. As the nails descend from

the magazine the edges of the plate 21^a engage the heads of the nails and draw them outwardly in both directions. In the channel 20 are fixed opposite inner walls 22^b, 60 lying nearer the central axis than the outer wall and against which the heads of the nails positioned by the plate 21^a strike to turn the point down. Access may be had to the channel through an opening normally 65 closed by a slide 22^c, operating between guides 22^d.

The feed-opening 19 is controlled by two adjacent closures or gates, these operating through an opening 23 in the inner wall of 70 the casing and being situated in a chamber 24 within the head. One of these closures consists of a plate 25, carried upon the end of a lever 26, said lever being fulcrumed in brackets 27, fixed to the casing and having its inner 75 angular end 28 contacting with a spring 29, which normally holds the closure in the position illustrated in Fig. 3 of the drawings. Extending along this spring 29 and the lever 26 is a flat spring 30, contacting with the 80 arm 28 and having an inturned end 31, furnishing the second closure, but normally lying outside the throat of the magazine.

The spring 30 is engaged by a contact-piece 32 projecting from an arm 33 of an operating member or slide 34. This slide extends along a groove 35, formed in the handle, and may be guided by a pin 36, operating through an elongated opening or slot 37. To the outer end of the slide is articulated one 90 arm of an angle-lever 38, fulcrumed at 39 in a recess or groove 40 in the handle.

In the head below the delivery-opening from the channel 20 and extending to the face of the shank is formed a groove 41, 95 continuing the channel. Intersecting this groove is a recess 42, in which is situated a controlling member or gate comprising a head 43 and a stem 44, extending through a bore 45 to the opposite side of the hammer-shank. In this head 43 is an opening 46, which may be brought into alignment with the groove 41, and outside this opening is a contact portion 47, furnishing a closure for the groove and a driving-face. In the extremity 105 of the gate-stem is a recess 48, engaged by a reduced end portion of an arm 49, depending from the operating member. About the shank is a groove 50, in which is situated a retaining-spring 51, which may be secured 110 in place by a screw 52. This spring is open or divided at 53, opposite the groove 41, and

the walls of the spring on each side of this opening are inclined or diverge inwardly at 54.

In use the magazine is supplied with nails, and these descend by gravity through the 5 throat, and the lowest one rests upon the plate 25. Now when it is desired to begin the feed the thumb-piece of the operating-lever is pressed inward. This brings the contact-piece against the spring 30, pressing it 10 against the angular portion of the lever 26, which is turned about its fulcrum, and this withdraws the plate 25 from the opening, allowing the lowermost nail to drop into the channel. At the same time the end 31 of the 15 spring passes across the opening and again closes it, there being sufficient space between these two closures to permit the movement while the nail is resting upon the plate, but not enough to admit a second nail. The operating-lever is now released, and the spring 20 30 exerts its tension to force the slide back, at the same time withdrawing the closure 31 and permitting the spring 29 to return the closure 25, upon which the succeeding nail is 25 deposited. The nail which has passed into the channel falls with its head in contact with one of the inner side walls 22^b, which retards its movement, turning the point downward, so that it enters the delivery-opening and 30 rests upon the portion 47 of the gate. A second pressure upon the operating-lever not only supplies the next nail to the channel, as has just been described, but brings the gate-opening into alignment with the delivery-opening, allowing the nail to fall into the 35 groove which continues the channel, in which it rests with its head supported by the walls 54 of the retaining-spring. The next release of the operating-lever restores the contact 40 portion 47 to its initial position, when it will be situated above the head of the nail, as is shown in Fig. 3, furnishing a contact-face, whereupon it may be driven into the work by a preliminary blow, giving sufficient engagement with the wood to enable the hammer to 45 be drawn away, the retaining-spring yielding to permit this. It will be seen that after the first operation there is always a nail in the channel ready to pass down into the position 50 for driving upon the operation of the lever to feed the next nail, and the driving may be continued until the supply in the magazine is exhausted. This device enables the workman to supply and drive the nails with one hand, leaving the other hand entirely free to hold or place the work. This allows such operations as shingling and lathing to be carried on with great speed.

Having thus described my invention, I 60 claim as new and desire to secure by Letters Patent—

1. A hammer comprising a nail-magazine having a feed-opening, and a plurality of adjacent closures successively controlling the 65 opening and having sufficient space between

them to receive a nail said nail lying lengthwise upon them.

2. A hammer comprising a nail-magazine having a feed-opening, a plurality of adjacent closures successively controlling the opening, 70 means for delivering a nail laterally to the closures, upon which it lies lengthwise and means for simultaneously moving the closures in opposite directions.

3. A hammer comprising a nail-magazine 75 having an opening, a closure for the opening, an operating member for the closure, and a spring acting upon the operating member, said spring furnishing a second closure for the opening.

4. A hammer comprising a nail-magazine having an opening, a closure for the opening pivoted adjacent thereto, and a spring acting upon the closure and furnishing a second closure. 80

5. A hammer comprising a nail-magazine having an opening, a closure for the opening pivoted adjacent thereto, a spring acting upon the closure and furnishing a second closure, and an operating member for both closures 90 contacting with the spring.

6. In a hammer of the character described, the combination with a hammer having a grooved handle and provided with a shank having a longitudinal groove and a recess intersecting the groove, of a gate in the said recess and provided with an opening, a stem on said gate projecting out through the recess, a slide in the groove of the handle and provided with a downwardly-extending arm 95 loosely engaging the stem of the gate, and means for operating the slide. 100

7. A hammer, comprising a nail-magazine having a feed-opening leading therefrom and a channel leading from the feed-opening, two 105 spring-closures, one operated by the other and adapted to alternately project into the feed-opening of the magazine, a hammer-shank, a gate sliding in the hammer-shank for closing the said channel, said gate furnishing a contact-face for a nail, a handle, a slide mounted in the handle, and separate means on the slide for engaging the gate and one of the closures to operate them. 110

8. A hammer comprising a nail-magazine 115 having a feed-opening leading therefrom and a channel leading from the feed-opening, two closures adapted to alternately project into the feed-opening, one above the other, means for operating one closure from the other, a 120 hammer-shank, a gate sliding in the hammer-shank and adapted to close the said channel, said gate furnishing a contact-face, and a slide having oppositely-projecting portions, one for operating one of the closures and the other for operating the gate. 125

9. The combination with a hammer-head provided in its contact-shank with a longitudinally-extending groove, of a nail-magazine supported upon the head and having a 130

contracted delivery-opening situated in alignment with the groove, and a spring surrounding the said shank and divided opposite said groove, each of the spring-sections exerting 5 its tension independently upon the nails in the groove.

10. The combination with a hammer-head provided in its contact-shank with a longitudinally-extending groove, of a nail-magazine 10 supported on the head and having a contracted delivery-opening situated in alignment with the groove, and a spring surrounding the shank and divided opposite said groove, the ends of the spring-sections 15 verging toward the magazine.

11. In a hammer, the combination of a magazine having a feed-opening, a pivoted and spring-pressed closure for the feed-opening, a second closure in the form of a spring 20 for the feed-opening, and above the first closure, means whereby the first closure will be operated by the second closure when the said second closure is operated and means for operating the second closure.

25 12. In a hammer, the combination of a magazine having a feed-opening, a pivoted and spring-pressed lever carrying a closure at one end for said feed-opening, a spring adjacent to said lever and having an inturned 30 end forming a second closure for the feed-opening, and a sliding member for engaging the spring.

35 13. In a hammer, the combination of a magazine having a feed-opening, a pivoted lever having an angular end, a closure for the

feed-opening on one end of the lever, a spring engaging the angular end of the lever, a flat spring adjacent the lever and having its end bent to form a second closure for the feed-opening, a sliding member having a contact-piece 40 for engaging the spring, and means for operating the sliding member.

14. In a hammer, the combination of a magazine having a feed-opening and a channel leading from the feed-opening, two closures 45 for the feed-opening, a gate for the channel, a sliding member having arms for operating the closures and gate, and means for operating the sliding member.

15. The combination with a hammer having a longitudinal groove and a transverse bore in its shank, of a magazine carried by the hammer-head and having a feed-opening, and a channel leading to the groove of the hammer-shank, a pivoted and spring-pressed 55 closure for the feed-opening, a spring acting upon the closure and forming a second closure, a gate in the channel and having its stem extending through the bore of the hammer-shank, a sliding member having arms, 60 one of said arms engaging the said spring and the other the stem of the gate, and means for operating the sliding member.

In testimony whereof I have signed my name to this specification in the presence of 65 two subscribing witnesses.
